UNITED STATES PATENT OFFICE.

EDWARD A. HALBLEIB, OF ROCHESTER, NEW YORK, ASSIGNOR TO NORTHEAST ELECTRIC COMPANY, OF ROCHESTER, NEW YORK, A CORPORATION.

ENGINE-STARTING APPARATUS.

1,074,790.

Specification of Letters Patent.

Patented Oct. 7, 1913.

Application filed July 8, 1910. Serial No. 571,099.

To all whom it may concern:

Be it known that I, EDWARD A. HALBLEIB, a citizen of the United States, and resident of Rochester, in the county of Monroe and State of New York, have invented certain new and useful Improvements in Engine-Starting Apparatus, of which the following is a specification.

This invention relates to apparatus by which an internal-combustion engine, particularly one of the multi-cylinder type, may be started without cranking or the exertion of force on the part of the operator.

The principal object of the invention is to produce an apparatus, of the kind above referred to, which may be conveniently used in connection with the engine of an automobile, or with any power-system in which an electric generator is actuated by the engine and employed to produce current for energizing the igniting devices of the engine, and for charging a storage-battery by which current may be supplied either to energize the igniting-devices, when the engine is first started, or to supply current to electric lamps or other electrically-operated devices. In my novel starting apparatus I employ such an electric generator not only for the ordinary purposes above described, but also as an element of the starting apparatus, the generator, in this connection, being caused to operate as an electric motor by means of current derived from the storage-battery, and the power so produced by the generator being employed to operate means by which one or more cylinders of the internal-combustion engine are charged with combustible mixture at suitable pressure, so that by a proper manipulation of the ignition-devices the engine may be started automatically from a condition of rest.

As incidental to the general mode of operation just described I employ, further, an automatic device by which the operation of the ignition-devices in starting the engine is automatically timed to occur when, but not before, the combustible mixture introduced, as above described, into the engine has attained a predetermined pressure sufficient to insure the starting of the engine when this mixture is ignited.

Other objects of the invention, and the features of construction by which they are

attained, will be set forth in connection with the following description of the illustrated embodiment of the invention.

In the accompanying drawings:—Figure 1 is a longitudinal vertical section of parts 60 of the mechanism of an engine-starting apparatus embodying the present invention, the figure showing particularly the automatic circuit-closer by which the ignition is controlled, the pump and the mixing-valve, and the driving mechanism by which the generator, the engine and the pump are inter-connected. In this figure the pump is shown in section on the line 11—11 in Fig. 2; Fig. 2 is a detail-view of the pump and the mixing-valve, shown in section on the line 12—12 in Fig. 1, looking from left to right in the latter figure; Fig. 3 is a vertical section of the cylinder-head and the valve through which the combustible mixture is introduced into the cylinder; Fig. 4 is a sectional plan-view of the distributing-valve by which the combustible mixture is distributed to the engine-cylinders, the section being taken on the line 14—14 in Fig. 5; Fig. 5 is a vertical section of the distributing-valve on the line 15—15 in Fig. 4, looking upward in the latter figure; and Fig. 6 is a diagram illustrating the entire arrangement of the electrical and mechanical portions of the starting apparatus.

My invention is illustrated as applied to a four-cylinder, four-cycle internal-combustion engine of the type usually employed in connection with automobiles. The four cylinders of the engine are illustrated diagrammatically and designated as 1, 2, 3 and 4, in the order in which the power-impulses succeed each other in the several cylinders. An inlet-valve and an exhaust-valve 5 and 6, respectively, and a spark-plug 7 are illustrated diagrammatically in the head of each cylinder, while the pistons are designated by the reference-number 8.

The means for supplying the combustible mixture to the cylinders during the normal operation of the engine are not illustrated, as they may be the ordinary means for this purpose, but the combustible mixture for starting the engine is introduced to the several cylinders through pipes 9, which are supplied through a distributing-valve represented generally by the reference-number 10 in Fig. 6. The valve has a rotary valve-member 16 which is rotated by connection

with a moving part of the engine so as to properly time its operation and correlate the position of the valve with the positions occupied by the several pistons when the engine is at rest. For this purpose the valve may be conveniently mounted upon the upper end of the half-time shaft 17 of the engine, this being the shaft usually employed to actuate the electric timing and distributing devices. The combustible mixture is supplied to the distributing-valve through a supply-pipe 18 connected with the pump and the mixing-valve, which latter are indicated generally by the reference-number 19 in Fig. 6. The pump is actuated by the electric device which operates normally as a generator, and the armature 20 of the generator is normally actuated, in the usual manner, by the engine, being connected therewith through a belt 21 and a pulley 22 on the engine-shaft. This pulley may be the fly-wheel itself of the engine.

The diagram illustrates a storage-battery 23 and the three field-windings 24, 25 and 26 of the generator. The winding 24 is a series-winding, while the winding 25 is a shunt-winding, the generator thus being of the compound-wound type. The winding 26 is arranged in series with the storage-battery and is wound in the opposite direction from the windings 24 and 25, thus constituting an opposition-winding. This latter winding acts to limit the magnetization of the generator-field, and thus to limit the output of the current when the generator is acting to charge the storage-battery, and in this manner overcharging of the battery is prevented.

A return-current cut-out 27 is introduced in the connections between the generator and the storage-battery, so that normally, when the generator is stopped owing to the stopping of the engine, current from the storage-battery cannot return through the generator to operate the latter as a motor. The construction of this cut-out is not illustrated, as such devices are well known.

The motor is illustrated diagrammatically as provided with an ordinary form of jump-spark ignition, the spark-plugs being connected with four secondary terminals of a quadruple induction-coil 28. The four primary windings are controlled by the usual circuit-controller or "timer", indicated generally by the reference-number 29 in Fig. 6. The timer is connected in the usual manner as, for example, by a rod 30, with the lever 31 by which the operator controls the timing of the ignition, and in this manner the fixed contacts of the timer are partially rotated about the half-time shaft 17 so as to vary the time of engagement with the rotating-contact 32.

In connection with the electrical apparatus above described, certain circuit-control-

lers peculiar to the present invention are employed to govern the ignition during the starting of the engine. A circuit-controller 33, adapted to be actuated by the lower end of the rod 30, operates to interrupt the normal ignition-circuit when the engine is to be started, while a pressure-operated circuit-closer 34 affords an alternative path for the current at such time. A pole-changing switch 35 is connected with the armature 75 and the series-winding 24 of the electric device, to reverse the connections thereof with the storage-battery, so that when the electric device operates as a motor its direction of rotation shall be the same as when it is operated as a generator. The pole-changing switch 35 is actuated by a mechanical connection with the circuit-controller 33.

The several parts of the apparatus diagrammatically illustrated in Fig. 6 will now be described in so far as they are novel and peculiar to the present invention. In Fig. 1 the end of the casing 36 of the generator is shown, the generator itself not being particularly illustrated as it may be of any ordinary or suitable form. The armature-shaft 37 of the generator is provided with a sleeve 38 having left-hand threads thereon, while collars 39 and 40 are pinned to the shaft 37 at the ends of the threaded sleeve. The sleeve is integral with the collar 39 so as to turn with the shaft.

The generator is connected with the engine through a belt, as hereinbefore described, this belt passing over a pulley 41 which runs freely on an annular ball-bearing 42 mounted on the bearing-boss of the generator-casing. The pulley is connected with a clutch-member provided with a circular series of teeth 43. A coöperating clutch-member is mounted upon the motor-shaft. This latter member comprises a nut 44 mounted to turn freely upon the threaded sleeve 38 and having clutch-teeth 45 adapted to coöperate with the teeth 43. Spring-pressed friction-blocks 46 are mounted in radial recesses in the nut 44, and their outer ends engage the inner cylindrical surface of the pulley 41. On its outer face the nut 44 is provided with a second series of clutch-teeth 47 which are adapted to coöperate with teeth 48 on a clutch-member fixed to the inner end of the pump-shaft 49.

The pump is illustrated as a rotary pump of a well-known type. It has a rotary piston 50 which operates in a casing 51 rigidly connected with the generator-casing. The inlet 52 to the pump (Fig. 2) is connected with a casing 53 in which is mounted a mixing-valve 54 by which combustible mixture is supplied to the pump. This valve is of a well-known form, and it is supplied with air through an inlet-opening 55 and with gasoline, or other spirit, through an inlet-passage 56, which is fed through a tube 57

- from a suitable source of supply. The flow of gasoline is controlled by the usual needle-valve 58, to regulate the proportions of the combustible mixture.
- 5 The driving-mechanism above described so operates that when the pulley 41 is rotated by the engine, which is the normal condition of affairs when the engine is running, the generator-shaft is rotated by the pulley, while the pump remains idle. On the other hand, when the engine is not running and the pulley 41 is at rest, if the generator be operated as a motor, the pump is actuated thereby, while the pulley is disconnected from the shaft. These operations occur through the longitudinal movement of the nut 44 upon the threaded sleeve. When the pulley 41 rotates, the friction of the friction-blocks 46 acts to rotate the nut 44 upon the sleeve, thereby moving it to the right and into engagement with the clutch-teeth 43 on the pulley. Through the action of these teeth, and through the engagement of the nut with the collar 42, the pulley is thus locked to the generator-shaft. On the other hand, when the pulley 41 is still, if the generator-shaft 37 rotate in the same direction as before by the motor-action of the electric device, the drag of the friction-blocks 46 against the inner surface of the pulley tends to prevent rotation of the nut, while the sleeve 38 rotates until the nut has been screwed to the left into engagement with the collar 39 and the clutch-teeth 48. Such engagement locks the generator-shaft 37 and the pump-shaft 49 together and the pump is then driven so long as the pulley 41 remains stationary, or until the pulley attains a speed of rotation greater than that of the generator-shaft.
- 10 The construction of the pressure-operated circuit-closer 34 of Fig. 6 is illustrated in Fig. 1. Integral with the pump-casing 51 is a diaphragm-casing 60 inclosing a corrugated diaphragm 61. This casing communicates, through an opening 62, with the pump-casing, so that the pressure in the diaphragm-chamber is always equal to that at the outlet of the pump. The diaphragm 61 engages an insulating button 63 fixed on a contact-spring 64, and the spring is mounted on an insulating plate 66 closing the end of the diaphragm-chamber. The contact-spring 64 co-operates with a fixed contact 67, which is mounted upon a screw 65 so that it may be adjusted toward and from the contact-spring. The two contacts are connected with binding-posts 68 and 69, by which they are connected in circuit with the other parts of the electric apparatus. By means of the screw 65 the circuit-closer may be so adjusted as to operate at any predetermined pressure in the diaphragm-chamber, and as this pressure corresponds with the pressure of the combustible mix-
- ture introduced into the engine-cylinders in starting the engine, the circuit-closer may thus be employed to operate the ignition-devices automatically upon the attainment of a predetermined pressure in the cylinders.
- 15 The construction of the distributing-valve 10 is illustrated particularly in Figs. 4 and 5. The rotary valve-member 16 is fixed to the upper end of the half-time shaft 17, and is inclosed within a casing 75 having a conical seat to which the valve is fitted. In the surface of the valve-seat the casing is provided with recesses or ports 76, each extending nearly 90° around the valve and each communicating with one of the pipes 9 leading to the several cylinders. A port 77 in the rotary valve-member extends to the upper part of the casing, which constitutes an inlet-chamber 78 supplied with combustible mixture through the pipe 18. A conical screw 79, which is adjustable in the top of the valve-casing, maintains the valve-member 16 in close engagement with its seat. When the engine is at rest the valve-member 16 occupies one of the four positions 90 analogous to that illustrated in Fig. 4, in which the valve-port 77 communicates with two of the ports 76, thus transmitting combustible mixture from the pipe 18 to the two engine cylinders in which the pistons 95 are on the expansion and compression-strokes, respectively.
- 20 The combustible mixture may be introduced into the engine-cylinders in any convenient way, but in the preferred embodiment of my invention it is introduced through devices in which check-valves, to prevent the escape of gases from the engine-cylinders during their normal operation, are combined with the valves commonly employed and designated as "priming-valves".
- 25 As shown in Fig. 3, the ordinary priming-valve 70 is provided with an extension 71 in which is formed a seat for a check-valve 72 which controls the admission of combustible mixture through the pipe 9. The check-valve is held to its seat by a spring 73 which is introduced through an opening closed by a screw-plug 74. By this arrangement I am enabled to introduce the combustible mixture for starting the engine through the same opening which is usually employed in connection with the ordinary priming-valve, and thus alteration of the engine-cylinder is entirely avoided.
- 30 I will now describe the operation of the system as a whole. Any ordinary four-cylinder engine tends to come to rest, when stopped and disconnected from the driving-mechanism of the vehicle, with all of the pistons about midway in the cylinders. This results from the fact that in two of the cylinders both the inlet-valves and the exhaust-valves are closed and equal volumes of gases are contained in these two cylinders, so that,

through the pressure of the gases, the pistons in these two cylinders tend to assume a position of equilibrium, that is, a position in which the gases in the two cylinders will have substantially equal pressures. When the engine is started from the position of rest one piston will be in position to finish an expansion-stroke already half-completed, a second piston will be in position to finish a compression-stroke, a third piston to finish a suction-stroke, and the fourth piston to finish an exhaust-stroke. In the diagram the pistons in these respective positions are designated as 1, 2, 3 and 4, respectively. According to the present invention the combustible mixture for starting the engine is introduced to those cylinders in which the pistons are on the expansion-stroke and the compression-stroke, namely, the cylinders 1 and 2 in the position of the parts illustrated in Fig. 6, for the reason that when so introduced two successive impulses may be produced in these two cylinders, which will be sufficient to carry the other two cylinders through a cycle of operations whereby the rotation of the engine may be continued and its normal operation initiated. This distribution of the combustible mixture to the proper cylinders is accomplished, as hereinbefore described, by the distributing-valve. In connection with this operation it is also necessary to provide for the ignition, first, of the cylinder in which the piston is on the expansion-stroke; and, as this requires a position of the electrical apparatus corresponding to a more retarded ignition than is employed in the normal running of the engine, provision is made for moving the timer to such position so that the appropriate contact may be made. After the engine has started to operate with all cylinders, however, the timing-device is returned, or allowed to return, to normal operating position.

The normal position of the apparatus, whether or not the engine be running, is illustrated in Fig. 6. Supposing the engine to be running in this position, the several parts rotate in the direction indicated by the arrows. The electric device now acts as a generator. Current from the armature 20 flows through a wire 80 to the upper arm of the pole-changing switch 35, and thence, through a wire 81, to the series field-winding 24 of the generator. After passing through the latter the current divides. A part of the current returns through the shunt field-winding 25 and through a wire 82, the lower arm of the pole-changing switch, and thence through wires 83 and 84 to the other brush. Another part of the current passes from the series-winding 24 through a wire 97 to the return-current cut-out and then through the storage-battery 23, from which it returns through a wire 91 and the opposi-

tion field-winding 26 to the wire 82, and thence back to the armature in the manner above described. A third part of the current, after passing through the return-current cut-out is conducted through a wire 85 to the circuit-controller 33, and from the fixed contact 86 of the latter it passes, through a wire 87, to a common terminal 88 of the primary windings of the compound induction-coil 28. Each of these primary windings has a second terminal, the latter being severally connected, through wires 89, with the several fixed contacts of the timer 29, so as to be successively in engagement with the rotating contact 32 of the timer. The current, after passing through the primary winding of such coil as may be in operation and through the contacts of the timer, is then conducted through the mechanical parts of the apparatus, which act in this respect as a ground for the current, and thus reaches the return-wire 82, which is shown in Fig. 6 as grounded, for this purpose, at the point 90 on the pipe 18. Through the return-wire 82 the current returns to the armature 20, as hereinbefore described.

With the engine at rest and the parts in the position above described, suppose the operator desires to start the engine. In this case the ignition-lever 31 is moved downwardly from the normal position illustrated in Fig. 6 against the opposition of a spring 98, thereby swinging the timer in such a manner as to bring into engagement with the rotating contact 32 the fixed contact corresponding to the cylinder 1. The ignition-apparatus does not operate at this time, however, for the same movement of the ignition-lever operates the circuit-controller 33 as before described, thereby interrupting the direct connection between the wires 85 and 87 and closing the shunt-circuit through the contact 92 of the circuit-controller and through the pressure-actuated circuit-controller 34. The same movement of the circuit-controller 33 acts, however, to throw the electric device into operation as a motor. This it does by engagement of its contact-arm with a fixed contact 95 which is connected, through a wire 96, with the wire 97. By this connection a short-circuit is formed around the electric valve, so that current is now free to return from the storage-battery through a wire 85 and through the circuit-controller and the wire 96 to the wire 97, and thence through the field-windings and the armature of the motor. At the same time that the above-described operations are performed the pole-changing switch 35 is reversed in position, so that the current flowing from the battery, as just described, passes through the armature of the electric device in such a direction as to cause the device to operate as a motor in the same direction of rotation in which it is actuated

when operating as a generator. The electric device now actuates the pump 19, thus forcing combustible mixture through the pipe 18, the distributing-valve, and the pipes 9 to the cylinders 1 and 2. As the pressure rises in these two cylinders it rises also in the circuit-controller 34 until finally the contacts of the latter engage each other. Current is now again conducted to the induction-coil by way of the wire 85, the fixed contact 92 of the circuit-controller 33, the fixed contact 93 of the circuit-controller 34, the movable contact of the latter, a wire 94, and the wire 87. This current returns through one of the wires 89 and through the contacts of the timer, and thence to the battery by way of the wire 82, the field-winding 26 and the wire 91. Upon the closing of the ignition-circuit, as just described, the spark-plug in the cylinder 1 is operated and a power-impulse occurs in this cylinder. After a partial rotation produced by this power-impulse the charge in the cylinder 2 is ignited in turn, and the two impulses thus produced suffice to start the engine in operation and to cause the cylinders 3 and 4 to operate in their turn. As soon as the operator perceives that the engine has started, he returns the ignition-lever to normal position, or he may release it and permit the spring 98 to return it automatically, and the parts are then restored to the normal position illustrated in Fig. 6, the engine operating in the usual manner and actuating the electric device as a generator to supply the current for ignition and to recharge the storage-battery.

It has heretofore been proposed to employ an electric device in connection with an internal-combustion engine, this electric device operating normally as a generator, but being used as a motor in order to start the engine. In such previously-proposed arrangements, however, the motor has been employed to actuate the engine mechanically, and thus throw it into operation, and it has been found that where such an arrangement is employed in connection with the largest and heaviest engines the consumption of battery-current is so great as to render the system unpractical and unsatisfactory. In the present arrangement, however, as the motor is used only to pump a small amount of combustible mixture into the cylinders, very little power is required, and the consumption of battery-current is trifling. This is particularly the case as it has been found in practice that with an ordinary four-cylinder engine only a very few seconds are usually required to start the operation of the engine. For this reason the present invention may be employed in connection with the usual batteries, generators, and other devices now employed with automobile engines, the only alterations neces-

sary being the addition of the pump and mixing-valve, the circuit-controllers, the distributing-valve and the wires and pipes by which they are connected. No alteration in the engine is necessary except the application of the distributing-valve to the upper end of the half-time shaft and the substitution of the special priming-valves hereinbefore described for the priming-valves of ordinary form.

The operation of the electric device in the same direction of rotation both as a generator and as a motor is a valuable feature of the arrangement hereinbefore described, as it avoids any shock to the mechanism at the time when the starting operation has been completed and the engine begins to actuate the device as a generator. At this time there occurs no change in its direction of rotation, and no substantial change in its speed of rotation.

Although I have illustrated the invention as applied to a four-cylinder, four-cycle engine, and as particularly useful in connection with motor-vehicles, it will be understood that it is susceptible of various other applications, and that it is not limited to the embodiment hereinbefore described and illustrated in the accompanying drawings, but may be embodied in various forms within the nature of the invention as it is defined in the following claims.

I claim:—

1. The combination, with an internal-combustion engine, of an electric device adapted to operate either as a generator or as a motor, said device being normally actuated by the engine as a generator, a storage-battery connected with and charged by the electric device, manually-operable means for connecting the battery with the electric device to energize the latter and operate it as a motor when the engine is not running, a charging pump adapted to be actuated by the electric device when so operating, and connections between the pump and the engine cylinders whereby one or more cylinders may be charged with combustible mixture to start the engine.

2. The combination, with an internal-combustion engine, of an electric device adapted to operate either as a generator or as a motor, a storage-battery connected with the electric device and adapted to receive current from or deliver it to the latter, a pump for charging the engine with combustible mixture to start the engine, and mechanism connecting the engine, the pump and the electric device, said mechanism operating automatically, when the engine is running, to actuate the electric device but not the pump, and, when the engine is not running and the electric device operates as a motor, to actuate the pump but not the engine.

3. The combination, with a multi-cylinder

- internal-combustion engine, of an electric device adapted to operate either as a generator or as a motor, a storage-battery connected with the electric device and adapted 5 either to receive current from or deliver it to said device, a pump for charging the engine to start it, connections between the pump, the electric device and the engine whereby the engine may actuate the electric 10 device, or the electric device may actuate the pump, connections between the pump and a plurality of cylinders of the engine, and distributing means operating automatically, in accordance with the position of the engine 15 parts, to control said connections between the pump and the cylinders so as to distribute the charge to the cylinders in which the pistons are in proper position for starting.
4. The combination, with a multi-cylinder 20 internal-combustion engine, of an electric device adapted to operate either as a generator or as a motor, said device being normally actuated by the engine, a storage-battery connected with the electric device and 25 adapted either to receive current from or deliver it to said device, a pump for charging the engine to start the latter, connections between the pump, the electric device and the engine whereby the engine may actuate the 30 electric device but not the pump, while the electric device may actuate the pump but not the engine, connections between the pump and a plurality of cylinders of the engine, and a valve actuated by the engine and controlling said connections to distribute the 35 charge to the cylinders in which the pistons are in the compression or the expansion-stroke.
5. The combination, with a multi-cylinder 40 internal-combustion engine, of an electric device adapted to operate either as a gener-

ator or as a motor, said device being normally actuated by the engine, a storage-battery, connections between the storage-battery and the electric device including an automatic return-current cut-out arranged to permit current to flow through the battery in a direction to charge the latter, a pump for charging the engine to start the latter, means for connecting the electric device with the pump to actuate the latter, and means under control of the operator for rendering said cut-out inoperative so as to permit the battery to energize the electric device when the pump is to be operated. 55

6. The combination, with an internal-combustion engine and its ignition apparatus, of an electric device adapted to operate either as a generator or as a motor, said device being normally actuated by the engine as a 60 generator, a storage-battery connected with and charged by the electric device, manually-operable means for connecting the battery with the electric device to energize the latter and operate it as a motor when the engine 65 is not running, a charging-pump adapted to be actuated by the electric device when so operating, connections between the pump and the engine cylinders whereby one or more cylinders may be charged with combustible mixture to start the engine, and means controlled by the pressure produced by the pump and connected with the ignition apparatus of the engine, said means operating automatically when a predetermined 70 pressure is attained to throw the ignition apparatus into operation. 75
